UNITED STATES PATENT OFFICE.

WILHELM A. SCHMIDT, OF ILION, NEW YORK, ASSIGNOR, BY MESNE ASSIGNMENTS, TO REMINGTON ARMS COMPANY, INC., OF NEW YORK, N. Y., A CORPORATION OF DELAWARE.

MACHINE FOR STRAIGHTENING BARRELS.

1,367,099.

Specification of Letters Patent. Patented Feb. 1, 1921.

Application filed December 13, 1918. Serial No. 266,619.

To all whom it may concern:

Be it known that I, WILHELM A. SCHMIDT, a citizen of the United States, residing at Ilion, in the county of Herkimer and State 5 of New York, have invented a certain new and useful Machine for Straightening Barrels, of which the following is a specification.

In a copending application I have described an improved process or method for straightening rifle barrel forgings which consist briefly in stretching the barrel, while hot, slightly beyond the elastic limit. While any machine capable of performing a stretching or pulling operation can be utilized to 10 carry out the process, I have found it necessary for an economical utilization of the process to employ a special machine which will rapidly perform the stretching operation. This machine forms the subject of this 15 application.

It is an object of my invention to provide a machine which will stretch rifle barrels or similar articles a short distance—as, for example, an inch or two—to thereby 20 straighten them and relieve all internal strains.

A further object is to provide a machine of this nature which will perform this work expeditiously and economically.

To this end it is a further object to provide such a machine having work-holding means which will quickly receive, grasp, stretch and release the work.

Other objects relate to certain structural 35 details as will later appear.

The invention is illustrated in the accompanying drawings in which—

Figure 1 shows my improved machine in perspective.

Fig. 2 is a side elevation thereof, certain parts being cut away to show the internal construction.

Fig. 3 is a perspective view of the draw-head, parts being broken away to show the 45 internal construction.

Fig. 4 is a vertical sectional view of the draw-head, and the holding collar, the barrel being shown in dotted lines.

Fig. 5 shows a central horizontal sec- 50 tional view of the draw-head.

Fig. 6 illustrates a horizontal section of a modified holding means which may be substituted for the holding collar shown in Fig. 4.

Fig. 7 is a plan view of another modified 55 form, while

Fig. 8 is a perspective view of a part of the structure shown in Fig. 7.

Referring to Fig. 1, the numeral 1 designates the base of the machine, 2 designates 60 a horizontally extending arm which may, if desired, be supported by the vertical standard 3. Spanning the space between the base 1 and the standard 3 I may provide a shelf 2' underlying the arm 2. 65

Referring more particularly to Fig. 2, the base 1 is provided with upwardly extending standards 13 and 14 which carry at their lower portions the horizontally extending shaft 8 carrying the belt pulleys 5 70 and 6, the pulley 6 being fastened to the shaft 8 for rotation therewith, while pulley 5 is loosely mounted on said shaft. Any suitable means 7 may be provided for shifting the driving belt from one of these pulleys to the other for starting or stopping the 75 machine, as is well understood.

The shaft 8 is provided with pinions 9 and 10. The pinion 9 engages with a large driving gear 11 which is journaled on a 80 bearing sleeve 12 mounted in the standard 13. The standard 14 supports a shaft 18' on which is mounted an idler pinion 18 which engages the pinion 10 and the gear 15' journaled on the sleeve 15 mounted in 85 the standard 14.

The ram 30 extends through the sleeves 12 and 15 and the gears 11 and 15' and its threaded rear end carries the nut 16 which is mounted for rotation but restricted 90 against longitudinal movement between the sleeves 12 and 15. Slidably mounted upon this nut and preferably feather-keyed thereto is the clutch collar 17 which carries jaws adapted for inter-engagement with 95 suitably arranged recesses on the gear 11 and is provided with a suitable clutch face for co-operation with the gear 15'. In this way it will be possible to connect either of these gears for rotating the nut 16. 100

It will be readily seen that if the shaft 8 is rotating in the proper direction and the clutch collar is moved against the face of the gear 11, the pinion 9 will rotate the gear 11 which will turn the clutch collar 17 and nut 16 and cause the ram 30 to be drawn backward; that if the clutch collar is moved to its central position no movement will be trans-

mitted to the nut and if it is moved against the gear 15' that the nut will be rotated in the opposite direction and that the ram will therefore be moved forward. This reversal 5 of direction is due to the intervening idler gear 18. It is also seen that while the backward movement of the ram is very slow its return movement will be comparatively rapid. The backward movement which is 10 the working stroke of the machine will therefore be accomplished with a high mechanical advantage, while the idle return stroke will be very rapid, to consume a minimum of time. In order to prevent a 15 possible overrunning of the nut and clutch collar it may sometimes be desirable to provide a brake for the collar such as the spring pressed brake 17'.

Any suitable means may be provided for 20 shifting the clutch collar, such as an arm 19' carried by a horizontally disposed shaft 19 journaled in the frame. The arm 19' carries a projection which is received in the groove 20 in the collar 17 for sliding said 25 collar, as is common in the art. Attached to the end of the shaft 19 is the crank 21 suitably connected by a link 22 with the lever 23 which is pivoted on a stud 24 attached to the arm 2. The upper end of this lever is 30 suitably connected to the rod 25 which is slidably supported in the bearing 26 carried by the arm 2. Adjustably mounted upon this rod are the collars 27 and 28 which may be secured at any desired point by set screws. 35 It is of course to be understood that this exact form of operating means for the clutch is not essential, but that any suitable means may be employed.

Fixedly secured to the front end of the 40 ram 30 for reciprocation therewith is the draw-head which is generally designated by the numeral 31. Suitable means are provided on the draw-head for coöperating with the collars 27 and 28. This means may consist of a laterally extending lug 32 which carries a pin 33 extending downwardly therefrom for engaging the collars 27 and 28.

This constitutes an automatic means for 45 stopping the movement of the draw-head at any desired predetermined point. Manual means are also provided for controlling the clutch. This may consist of a shaft 33' suitably journaled in the arm 2 and carrying at one end a crank 34 which may be connected 50 to the rod 25 by any desired means such as the connecting link 34'. The other end of the shaft 33' is provided with an arm 35, to the upper end of which is suitably connected a control rod 36 which has a bearing in a 55 bracket 37 and may be provided with a handle 38. It will be understood that the reciprocation of the rod 36 will reciprocate the rod 25, rotate the shaft 19 and shift the clutch collar to any desired position.

65 The draw-head will now be described in

detail. (See Figs. 3 and 4.) The draw-head may generally consist of the two parts 70 40 and 41, one of these parts being provided with any suitable slot such as the T slot 43, the other part being provided with a correspondingly shaped tongue 44 to be received in said slot. The sides of the drawhead may be provided with grooves 42 which have a bearing on guide ribs 42' formed on the 75 arm 2. This will provide a suitable support for the draw-head and while permitting sliding movement will nevertheless prevent rotation of the draw-head and its attached ram.

Part 41, which may be formed in two 80 parts held together by bolts 41', is provided with an interior cavity formed by the vertical walls 44' and the substantially horizontally extending walls 45. This cavity is open toward the front end of the head to receive the barrel to be stretched. It will be noted that while the walls 44 may be substantially parallel, the walls 45 are not so, but converge toward the front part of the head. Mounted within this cavity are the 90 jaws 46 and 47 provided with substantially parallel faces 47' facing each other and suitably serrated to grip the work. To provide for the suitable guiding of the jaws it may be necessary to provide them with guide 95 grooves 48 and 49 parallel to their back surfaces, pins 50, which may be formed as screws, being mounted in the draw-head to project into the guide grooves.

The rear part of each of the jaws is provided with lugs 51 and 52 which receive the pin 53 which holds the jaws alined and upon which is mounted the rack bar 54 slidably mounted in the head. A pinion 55 is carried by a shaft 56 rotatably mounted in the bearing bushings 57 and 58. Attached to the upper end of this shaft is the crank 59. Suitably connected to the crank 59 is an operating rod 60 which may be provided with a handle 61. This rod is supported by the 100 brackets 62 and 63, bracket 62 being supported by the draw-head and moving therewith, while the bracket 63 is carried by the 105 arm 2.

The draw-head may be provided with a 110 suitable bracket, such as the one shown at 42', with an axially disposed aperture for receiving and guiding the end of the forging to be stretched.

Referring now to Fig. 4, the face plate 65 115 is suitably attached as by bolts 66 to the end of the arm 2. Secured to this face plate is the holding collar 67 suitably attached thereto as by bolts 68. The face plate is provided with a central aperture 69 to permit the insertion of the work into the machine. This type of holding collar can be used only when working on barrels or other articles which have an enlarged end as is usual in high power rifles such as military arms. 125

The operation of the machine is as follows: The collars 27 and 28 are properly adjusted on the rod 25, the shaft 8 is set to rotating in the proper direction and the 5 clutch is placed in neutral position with the draw-head in its forward position. The barrel which is shown in dotted lines in Fig. 4 is now inserted through the collar 67 and is forced between the jaws 46 and 47 which 10 receive the small end of the barrel. The opening of the jaws may have been previously effected by manipulating the operating rod 60. When the barrel has been inserted in the machine so that its enlarged end contacts with the collar 67 the operator will push 15 the rod 60 backward. This will cause the jaws to be slid forward and the coöperation of their inclined back surfaces with the inclined surfaces 45 of the cavity will cause 20 the jaws to be clamped upon the barrel. The operator now pulls the operating rod 36 forward, which will rock the clutch arm 19' to cause the clutch to be engaged with the drive gear 11, which will rotate the nut 25 16 and cause the ram and draw-head to be drawn backward to straighten and stretch the barrel.

It will readily be seen that the tension on the barrel will cause the jaws to move 30 forward in the head and to be wedged tighter against the barrel. It is obvious that the elongation of the barrel will continue until the pin 33 strikes the collar 28 and moves the rod 25 sufficiently to cause 35 the disengagement of the clutch collar from the gear wheel 11. The movement of the draw-head will then stop. This movement of the rod 25 is not sufficient to cause the engagement of the clutch with the gear 15' 40 and it will now be necessary for the operator to push the rod 36 rearwardly, which will cause the rapid return of the draw-head, and permit the release of the jaws from the work by the manipulation of the 45 operating rod 60.

It will often be desirable to use this machine for straightening barrels or other articles which are not formed with enlarged ends, in which case means will necessarily 50 be provided for gripping the forward end of the work also. This result may be obtained by the modified construction shown in Fig. 6, wherein the usual face plate 65 is provided with a holding head 70 suitably 55 attached to the face plate as by bolts 71. This holding head is provided with a wedge shaped cavity similar to the one in the draw head and similar jaws 72 are provided for gripping the work. These jaws may be 60 wedged against the work by any desired means, such as, for example, a link 73 pivoted to a pin 73' operated by a hand lever 76 pivoted at 75 to the holding head 70.

In Figs. 7 and 8 I have shown another 65 modified form of my invention, showing it

adapted for pulling straight barrels or barrels substantially cylindrical. When this construction is used, face plate 65 is removed and in its place is substituted a holding head which may comprise a special form 70 of face plate 80 to which is secured, preferably by a T slot connection, a casing composed of the two halves 81 and 82 bolted together by bolts and nuts 83. The casing is provided with a tapering internal cavity 75 similar to the cavity in the drawhead 31, in which are located the complemental jaws 85 and 86 similar to the jaws in the draw-head. Each of these jaws is provided on its opposite sides with grooves 87, parallel 80 with their outside faces. The casing carries a number of pins 88, preferably threaded therein, projecting into these grooves. The purpose of these pins is the same as that of pins 50, namely, to open the jaws when 85 they are retracted. The rear ends of the jaws are provided with projections 85' and 86' provided with aligned openings for receiving the pin 89. Upon this pin is mounted a rack 89' which lies in a depression 90 formed in the jaws. Coöoperating with this rack is a pinion 90 mounted on a shaft 90' which has half of its bearing in the casing part 82. The other half of the bearing is formed in a plate 91 bolted as at 92 to the 95 casing part 82. Attached to the shaft 90', preferably by means of a nut 90", threaded on a threaded extension of the shaft, is the arm 93.

The operation of this part of the device is 100 obvious. When the arm 93 is drawn back, the shaft 90' is rotated, carrying with it the pinion 90 which draws the rack 89' to the left carrying with it the pin 89 and the jaws 85 and 86. On account of the inclined 105 surface of the jaws they are forced together and grip whatever is placed between them.

It is obvious that the arm 93 could be operated directly by the hand of the operator but since the jaws 85 and 86 will generally be operated at the same time that jaws 46 are operated, I have found it desirable to provide some means so that both sets of jaws may be operated by a single 110 control means. In order that both jaws may firmly clamp upon the forging, which is likely to vary considerably in diameter, it will be necessary to provide a construction wherein the clamping of one set of jaws 115 upon the work will cause them and their operating connections to act as a fulcrum to permit the operation of the other set of jaws, and where the connecting parts will not interfere with the relative movement between the two sets of jaws. These results 120 are obtained by providing the hand lever 96, preferably provided with a handle 97, pivotally connected to the arm 93 as at 98. At the end of the lever 96 is pivoted a link 130

100, as at 99. The other end of the link is pivoted, as at 101, to the arm 59 which controls the jaws in the movable draw-head 31.

I have found it desirable to provide a 5 stop 94, preferably attached to the face plate 80, to limit the forward motion of the arm 93. Similarly, a stop 95 may be provided to limit the motion of the arm 59. The outer end of the lever 96 may be bent upward 10 as at 102 to prevent interference of the parts. In the operation of the machine, the handle 97 is pushed forward until the arms 93 and 59 abut their respective stops. The jaws will then be open and the forging 103 may 15 be passed through the space between the jaws 85 and 86 and between the jaws 46 and 47. The lever 96 is then drawn backward as far as possible. This causes the arm 93 to be rocked backward until the 20 resistance set up by the closing of the jaws upon the work permits the lever 93 to act as a fulcrum and causes the link 100 to rock the arm 59 to jaw closing position. It is of course obvious that the other set of jaws 25 may be closed first, in which event the arm 59 will provide a fulcrum permitting the application of the force to the arm 93. It will be seen also that the connections shown will not interfere with the motion of the 30 draw-head. Another advantage of this construction is that the same system of levers may be used with forgings which vary considerably in length.

It will be readily seen that I have provided 35 a machine which will effectively and economically stretch and straighten barrels or other like articles, and while the machine is of special application for working on rifle barrels it is evident that it may also be effectively used for stretching articles of any 40 kind and that its details—as for example, the jaw construction—may be useful in other relations. While I have described my improved machine in more or less detail to comply with the requirements of the 45 statute, it is nevertheless desired that this detailed description be considered merely as illustrative and not as limiting, and it is to be understood that changes and modifications in the machine may be made by those 50 skilled in the art without departing from the invention as defined in the following claims:—

1. In a machine for stretching rods, the 55 combination of a support, stationary holding means carried by the support, a movable drawhead slidably mounted on said support, said drawhead being provided with a cavity and gripping jaws in said cavity, said cavity and jaws being so constructed as to cause 60 opening and closing of the jaws when moved lengthwise in said cavity.

2. In a machine for stretching rods, the 65 combination of a support, stationary holding means carried by the support, a mov-

able drawhead slidably mounted on said support, said drawhead being provided with a cavity, gripping jaws in said cavity and manual means for sliding said jaws in the cavity.

3. In a machine for stretching rods, the combination of a support, stationary holding means carried by the support, a movable drawhead slidably mounted on said support, said drawhead being provided with a cavity, gripping jaws in said cavity, said cavity and jaws being so constructed as to cause opening and closing of the jaws when moved lengthwise in said cavity and manual means for sliding said jaws in the cavity whereby said jaws may be manually opened and closed.

4. In a machine for stretching rods, the combination of a support, stationary holding means carried by the support, a movable drawhead slidably mounted on said support, said drawhead being provided with a cavity, gripping jaws in said cavity and manual means for sliding said jaws in the cavity, said means comprising a pinion in 90 said drawhead and means connected to the jaws and coöperating with said pinion whereby rotation of said pinion will move the jaws in the cavity.

5. A machine for stretching rods, comprising a drawhead having a cavity formed with converging walls, jaws in said cavity coöperating with said walls and rack and pinion means for moving said jaws in the cavity.

6. A machine for stretching rods, comprising a drawhead having a cavity formed with converging walls, jaws in said cavity coöperating with said walls, and rack and pinion means for moving said jaws in the 105 cavity, said means comprising a rack connected to the jaws and a pinion coöperating therewith.

7. A machine for stretching rods, comprising a drawhead having a cavity formed 110 with converging walls, jaws in said cavity coöperating with said walls and means positively guiding the jaws for movement parallel to said converging walls.

8. A machine for stretching rods, comprising a drawhead having a cavity formed with converging walls, jaws in said cavity coöperating with said walls and means positively guiding the jaws for movement parallel to said converging walls, said means comprising guide grooves in one of said parts receiving projections carried by the other.

9. A machine for stretching rods, comprising a drawhead having a cavity formed with converging walls, jaws in said cavity coöperating with said walls and means positively guiding the jaws for movement parallel to said converging walls, said means comprising guide grooves in said jaws receiving projections carried by the drawhead.

10. A machine for stretching rods, comprising a drawhead having a cavity formed with converging walls, jaws in said cavity coöperating with said walls and means positively guiding the jaws for movement parallel to said converging walls, said means comprising guide grooves in said jaws receiving removable projections carried by the drawhead. 5
11. A machine for stretching rods, comprising a drawhead having a cavity formed with converging walls, jaws in said cavity coöperating with said walls and means positively guiding the jaws for movement parallel to said converging walls, said means comprising guide grooves in said jaws receiving screws carried by the drawhead. 15
12. A machine for stretching rods, comprising a drawhead having a cavity formed with converging walls, jaws in said cavity coöperating with said walls, aligned openings in said jaws, a pin in said openings and means connected to said pin for sliding said jaws. 20
13. A machine for stretching rods, comprising a draw-head having a cavity formed with converging walls, jaws in said cavity coöperating with the said walls, aligned openings in said jaws, a pin in said openings and means connected to said pin for sliding said jaws, said means comprising a rack attached to the pin and a pinion coöperating with said rack. 25
14. A machine for stretching rods, comprising a draw-head having a cavity formed with converging walls, jaws in said cavity coöperating with said walls, aligned openings in said jaws, a pin in said openings and means connected to said pin for sliding said jaws, said means comprising a rack attached to the pin and a pinion coöperating with said rack, a shaft trunnioned in said draw-head and means for rotating said shaft. 35
15. In a machine for stretching rods, a movable draw-head, a stationary holding head, rod gripping jaws in said draw-head and holding head, external means for operating said jaws and a single control means for actuating said jaw-operating means at will. 40
16. In a machine for stretching rods, a movable draw-head, a stationary holding head, rod gripping jaws in said draw-head and holding head, external means for operating said jaws and a single manual control means for actuating said jaw-operating means at will. 45
17. In a machine for stretching rods, a movable draw-head, a stationary holding 50
- head, rod gripping jaws in said draw-head and holding head, external means for operating said jaws and a single manual control means for actuating said jaw-operating means at will, said control means being so constructed and arranged that the reaction of either set of jaws will set up a fulcrum for the operation of the other set. 65
18. In a machine for stretching rods, a movable draw-head, a stationary holding head, rod gripping jaws in said draw-head and holding head, external means for operating said jaws and a single control means for actuating said jaw-operating means at will, said control means being so constructed and arranged that it will permit the necessary relative motion between the draw-head and the holding head. 70
19. In a machine for stretching rods, a movable draw-head, a stationary holding head, rod gripping jaws in said draw-head and holding head, external means for operating said jaws and a single control means for actuating said jaw-operating means at will, said control means being so constructed and arranged that the reaction of either set of jaws will set up a fulcrum for the operation of the other set, and to permit the necessary relative motion between the draw-head and the holding head. 80
20. In a machine for stretching rods, a movable draw-head, a stationary holding head, rod gripping jaws in said draw-head and holding head, external means for operating said jaws and a single control means for actuating said jaw-operating means at will, said control means comprising a hand lever pivoted to the operating means for one set of jaws and pivoted at another point to a link connected to the operating means for the other set of jaws. 85
21. In a machine for stretching rods, a movable draw-head, a stationary holding head, rod gripping jaws in said draw-head and holding head, operating means for each set of jaws comprising crank arms, a hand lever pivoted to one of said crank arms and provided with means for operating the other crank. 90
22. In a machine for stretching rods, a movable draw-head, a stationary holding head, rod gripping jaws in said draw-head and holding head, operating means for each set of jaws comprising crank arms, a hand lever pivoted to one of said crank arms and a link pivoted to another part of said hand lever and to the other crank arm. 95

In testimony whereof I affix my signature.

WILHELM A. SCHMIDT.
